UNITED STATES PATENT OFFICE.

THEODORE W. MAVES, OF MINNEAPOLIS, MINNESOTA.

OVEN FOR BURNING OUT INVESTED MODELS.

1,279,738.

Specification of Letters Patent. Patented Sept. 24, 1918.

Application filed April 24, 1918. Serial No. 230,451.

To all whom it may concern:

Be it known that I, THEODORE W. MAVES, a citizen of the United States, resident of Minneapolis, county of Hennepin, State of Minnesota, have invented certain new and useful Improvements in Ovens for Burning Out Invested Models, of which the following is a specification.

In making dental castings, it has been customary to provide a flask in which a wax model or pattern of the shape of the cavity to be filled or of the form of the desired casting is placed and surrounded by what is known as "investment" material, with a sprue rod mounted in the wax model and extending outwardly through the investment material. The wax model is then melted to be absorbed by the surrounding material, and the sprue rod having been previously removed, a matrix will be formed into which the molten metal is poured to form the desired casting or inlay.

The object of my present invention is to provide improved means for melting the wax model to the end that this part of the work can be neatly and expeditiously performed.

The invention consists generally in various constructions and combinations, all as hereinafter described and particularly pointed out in the claims.

In the accompanying drawings forming part of this specification,

Figure 1 is a vertical sectional view through an oven embodying my invention,

Fig. 2 is a plan view with the cover removed, showing the support for the flasks above the heater,

Fig. 3 is a plan view of the heater proper,

Figs. 4 and 5 are detail views of the covers for closing the holes for the flasks when not in use.

In the drawing, 2 represents the base of the heater, having suitable supporting legs 3 and provided in its upper surface with a series of transverse grooves or recesses 4 in which a resistance coil 5 is placed and embedded in a suitable plastic material 6. The ends of the coil are in circuit with an electric conductor 7 through which a current is passed to heat the resistance wire 5 and the space above the heater forming the oven. The resistance coil is so made or formed that when the current is turned on the oven will

be heated to a certain temperature which I have found best suited for melting the wax and by equipping the heater with a coil for producing a certain degree of temperature I am able to determine how long the flask should be in the oven to melt the model.

The base or bed of the heater has a recess or shoulder formed therein at 8 whereon a casing 9 is seated. This casing is made preferably of metal, rectangular in form to fit snugly down over the top of the base and form a heating chamber for the oven 10 above the base. Ledges 11, preferably of angle bar, are secured to the casing 9, preferably at a point midway between the top and bottom of the casing and form supports for a floor plate 12 that is seated loosely on the ledges 11 and forms the top or roof of the oven chamber 10. This plate 12 is provided with a comparatively large central opening 13 and a series of smaller openings 14 arranged around it and I preferably provide flanges 15 and 16 encircling these openings and spaced from the edges thereof to form ribs or ledges 17. The flanges 15 and 16 have openings 18 therein and cover plates 19 fit within the flanges and close the openings in the plate 12 and have finger grips 20 which project through the openings 18. These cover plates close the openings until such time as the operator desires to insert a flask therein, when the plate will be removed and the flask, with the wax model therein, placed in the opening with its lower portion depending into the oven 10. The lower portion of the flask will be sufficiently near the top of the heater so that the wax will be quickly melted and absorbed by the investing material. By providing openings of different sizes in the plate 12 I adapt it for flasks of different diameter, according to the size of the casting required.

The top of the casing is closed by a cover plate 21 having a series of vent holes 22 therein, one above each opening, and a hand grip 24 which has a central vent opening 25. When this cover is removed, access may be had to the plate 12 and the flasks therein. This plate, as shown, is preferably supported about midway between the top and bottom of the casing, so that there will be ample room above the supporting plate for the top of the flasks and for the sprue rods therein.

With this apparatus one or more flasks may be heated simultaneously and the wax models or patterns easily and quickly melted, leaving a matrix in each flask from which 5 the casting or inlay may be formed.

The flask supporting plate must be a certain predetermined distance from the heater to obtain the best results, but not too near or the wax will be burned out or melted 10 too quickly and if too far away the wax will be melted too slowly and too unevenly to obtain a finely finished casting. A degree of heat that is too low to uniformly melt the wax will be fatal to the successful operation 15 of the device for if the melting is not uniformly obtained the casting will not be smooth and will not be a duplicate of the wax pattern and hence will not fit the tooth. Over-heating will cause the investment to 20 crack and produce a defective casting. The best results are obtained by providing a slow, gradual heating of the oven and the walls of the flask depending therein and by making provision for this slow, gradual heating I 25 am able to produce a smooth, accurately formed casting which will be an exact duplicate of the wax and be a perfect fit for the tooth.

The device may be made in various sizes 30 and the oven may be modified in various ways and still be within the scope of my invention.

I claim as my invention:

1. An apparatus of the class described, 35 comprising a base having a heating means mounted therein, a casing mounted on said base, and a flask supporting means arranged within said casing and spaced from said heating means to form a dry heating chamber into which the flask carried by said means depends.

2. The combination, with a base having an electric heating coil mounted therein, of a casing surmounting said base, a plate supported within said casing intermediate to the top and bottom thereof and having a plurality of openings therein adapted to receive flasks for making dental castings, the space between said plate and said base forming a closed heating oven into which said flasks depend.

3. The combination, with a base having a heating means mounted therein and a casing surmounting said base, of a plate supported within said casing and spaced from said base to form a heating oven, said plate having a plurality of holes therein and flanges encircling said holes and spaced from the edges of said openings, and cover plates fitting

within said flanges and covering said openings, and a suitable cover for said casing.

4. An apparatus of the class described comprising a base having an electric heater therein for producing a predetermined degree of heat, a casing supported by said base, a flask carrier fitting within said casing and spaced from said heater to form an oven, said carrier having an opening therein to receive a flask containing a wax model and investment material, said flask depending through said carrier into said oven and being heated by the predetermined degree of heat therein to melt said model.

5. An apparatus of the class described comprising a base having a heating means mounted therein, a casing mounted on said base, a flask carrier arranged within said casing and spaced from said base to form an oven, and a flask mounted in said carrier and depending therethrough into said oven, said heating means being constructed to provide a gradual uniform heat in said oven around the walls of the flask depending therein.

6. An apparatus of the class described comprising a base having an electric heating coil mounted therein for producing a predetermined degree of heat, a casing surmounting said base, a flask carrier supported within said casing and spaced from said heater to form an oven, said carrier having a comparatively large central opening therein and a series of smaller openings encircling said central opening adapted to receive flasks containing an investment material and wax models, said flasks depending into said oven and heated uniformly by said coil to melt said models in a predetermined time.

7. An apparatus of the class described comprising a base, an electric heating coil mounted therein, a casing supported by said base and having an open top and cover therefor, a flask carrier fitting within said casing and supported intermediate to the top and bottom thereof and spaced from said heating coil a sufficient distance to form an oven which is closed to the escape of heat, said carrier having openings to receive flasks containing investment material and wax models, said flasks depending within said oven and being subjected to the predetermined degree of heat therein for melting the wax models in a given time, and said carrier having means for closing the openings therein which are not in use.

In witness whereof, I have hereunto set my hand this 29th day of March 1918.

THEODORE W. MAVES.
